MECHANICAL SELF-ADJUSTING
MECHANISM

Harry E. Voorhies, Grosse Pointe Woods, Mich.,
assignor to Eaton Manufacturing Company,
Cleveland, Ohio, a corporation of Ohio

Application July 23, 1945, Serial No. 606,583

9 Claims. (Cl. 123—90)

1

This invention relates to valve operating mechanism for internal combustion engines and more particularly to mechanical self-adjusting tappets for operating the valves of such engines.

Broadly the invention comprehends self-adjusting mechanical tappets for use in the valve gear train of an internal combustion engine having cam mating parts incorporated therein relatively rotatable one to another adapted to compensate for changes in the operating length of the valve gear train and maintain the gear train at proper operating length.

An object of the invention is the provision of a mechanical self-adjusting mechanism adapted to automatically compensate for operating length of members associated therewith.

Another object of the invention is the provision of a self-adjusting mechanical tappet of simple construction and efficient operating characteristics.

Another object of the invention is the provision of an automatic adjustable mechanical tappet having means incorporated therein providing quick and quiet adjustment in compensating for the operating length of the tappet.

A further object of the invention is the provision of a mechanical tappet having cam mating means incorporated therein providing for self-adjustment of the tappet.

A further object of the invention is the provision of a mechanical tappet having cam mating relatively rotatable parts providing for compensation in operating length of the tappet.

Other objects and advantages of the invention will appear from the following description taken in connection with the drawings, forming a part of the specification; and in which,

Fig. 1 is a partially fragmentary vertical sectional view taken diametrically through a tappet embodying the features of this invention showing it in connection with cooperating engine parts;

Fig. 2 is an enlarged sectional view taken through line 2—2 of Fig. 1;

Fig. 3 is a vertical sectional view of a pair of cam mating parts of the tappet; and

Fig. 4 is a vertical sectional view of another pair of cam mating parts of the tappet.

The tappet devised by the present invention relates to that type which includes a cylinder and cooperating plunger interposed between a cam and a valve operated thereby, the load carried by the tappet being primarily the force transmitted therethrough by the cam to open the valve and the movement of the plunger in the cylinder being resisted under such load by

2

means cooperating with the cylinder and plunger. In this type of tappet construction spring means are provided which constantly bias the plunger outwardly in the cylinder to increase the effective length of the tappet whereas cooperative parts interposed between the cylinder and the plunger provide means whereby the effective length of the tappet is slightly shortened under normal operating conditions. Because of the inherent structure providing for automatic self-adjustment, this type of tappet is effective to compensate in both directions for contraction and expansion of the valve stem and its associated members occasioned by temperature variations, as well as the wear of said parts.

In the present invention the means incorporated between the plunger and cylinder effective to provide for the contraction and the expansion of the tappet consist of two pairs of cam mating members, each of said pairs of members being rotatable relative to one another such that because of their cam mating surfaces are moved axially relative to one another upon the relative rotation thereof. The plunger which constitutes one of the cam mating members is coupled to one of the other pair of cam mating members such that these members may be solely axially movable relative to one another; whereas, the corresponding members associated respectively with the plunger and the member coupled to the plunger are securely held together.

A spring for extending the plunger relative to the cylinder is interposed between the plunger and the member coupled thereto such that when the tappet and its constituent members are in assembled position in a valve gear train wherein the valve stem engages the plunger and an engine cam engages the base of one of the cam members at the opposite extremity of the tappet, the cam mating surfaces assume a friction mating relationship normally resisting contraction in the operating length of the tappet whereas at the same time should contraction or wear occur in the valve gear train the tappet spring would function to extend the tappet and thereby take up the clearance in the valve gear train. Similarly should the valve stem or any of its associated members expand beyond their normal length the tappet would operate to contract in length, said contraction occurring due to the valve spring load imposed upon the plunger opposing the tappet spring and also the friction occurring between the respective cam mating surfaces.

Although the valve spring is not normally of

3

sufficient force to overcome the combined tappet spring load and the friction forces set up between the cam mating surfaces, the vibration transmitted through the tappet due to its reciprocable action with and between the cam and valve stem is sufficient to momentarily relieve the surface friction set up between the cam mating surfaces and thereby permit relative rotation and axial movement between the respective cam mating members.

For the purpose of obtaining a mechanical advantage in movement between the plunger and the member coupled thereto for axial relative movement, a different pitch is given to the respective pairs of cam mating members so that the axial movement of the plunger is multiplied in terms of axial movement of the member coupled to the plunger. The mechanical advantage to be selected will depend upon numerous factors such as valve spring load, tappet spring load, required limits of expansion and contraction in the valve train, and other reasons.

With reference to the drawings for more specific details of the invention, 10 represents generally a valve tappet reciprocable in a tappet guide sleeve 12 interposed between the end of the stem of the conventional poppet valve 14 urged downwardly by a valve spring, not shown, and a cam 16 mounted upon a conventional cam shaft 18.

The tappet 10 comprises a pair of cam members 20 and 22 securely fastened together by a pin 23, the cam member 20 having an enlarged cam contacting head 24 adapted to be engaged by cam 16, whereas, cam member 22 is received for reciprocation in the tappet guide sleeve 12. The members 20 and 22 respectively are provided with cam surfaces 26 and 28, said surfaces being similar in configuration but differing in pitch, the cam surface 28 of member 22 having a greater pitch than the cam surface 26 on the member 20. The cam surfaces 26 and 28 are arranged concentric to one another such that the peaks A and A¹ and lowest points B and B¹ of the cam surfaces are substantially in radial alignment.

The cam mating surfaces 26 and 28 are adapted to be engaged respectively by cam mating surfaces 30 and 32 respectively of plunger 34 having a head thereon 36 engaged between valve stem 14 and a cylindrical member 38 coupled to the plunger so as to be axially moveable relative thereto and reciprocable in the step bore of the tappet body.

The plunger 34 is coupled to the member 38 by a pair of pins 40 received in grooves 42 in the plunger 40 and grooves 44 in the member 38. In the assembly of the plunger 34 and member 38 the cam surfaces 30 and 32 are misaligned relative to one another; that is, peaks C and C¹ and lowest points D and D¹ of the cam surfaces 30 and 32 are not in radial alignment with one another so that the pairs of cam surfaces 26 and 30, and 28 and 32 can never both be in complete mating relationship at any time. The cam surfaces 30 and 32 are of equal pitch and complementary configuration respectively with cam surfaces 26 and 28 of members 20 and 22.

Fig. 1 illustrates clearly the arrangement of the respective cam surfaced members whereby upon contractive axial rotative movement of plunger 34 clockwise in Fig. 2 upon and relative to member 20, the cylindrical member 38 is extended axially upon and relative to member 22 by its rotation thereof, the simultaneous axial movement of member 38 and plunger 34 in opposite direc-

4

tions resulting in compression of a spring 46 one end of which is seated on a shoulder 48 of member 38 and the other end seated on a shoulder 50 of plunger 34.

Because of the difference in pitch provided between the respective pairs of cam mating surfaces, the cylinder member is adapted to move a greater true axial distance than the plunger, the relative axial distance being in proportion to the pitch ratio of the cam surfaces and furthermore a mechanical advantage is obtained corresponding to the ratio of movement occurring along the respective pairs of cam mating surfaces.

The cam surfaces 26, 28, 30, and 32, as shown by the drawings, although preferably made on a true helix so as to effect maximum bearing relationship between the respective pairs of cam mating surfaces thus providing for greater and more uniform distribution of wear, may be made of any suitable angular construction consistent with the purpose here intended.

In a normal operation of tappet 10 wherein the tappet is interposed in the valve gear train as shown by Fig. 1, the tappet assumes and maintains an extended position such that no clearance occurs between the various members going to make up the valve gear train.

Upon contraction or wear of any of the members in the valve gear train with the exception of the tappet, the tappet spring 46 operates to move the plunger 34 axially outwardly with respect to the member 38; and simultaneously, changes the mating positions of the respective pairs of cam mating surfaces.

With the taking up of the clearances in the valve gear system, the combined action of the spring and cam mating surfaces 26 and 30, and 28 and 32 cooperate to maintain the tappet in its newly extended position thereby providing for efficient and noiseless operation of the valve gear system. Should elongation occur in the valve gear system such as the expansion of the valve stem, a pressure additional to the normal valve spring pressure would be imposed on the tappet and the tappet in turn would function to be contracted an amount equal to the expansion of the valve stem, said contraction occurring due to additionally imposed load on the plunger and the vibration that is transmitted to the tappet in its reciprocation together with the valve gear system, tending to relieve the friction occurring between the pairs of cam mating surfaces.

It is to be observed that a relative axial movement occurring between plunger 34 and member 38 results in rotation between the respective pairs of mating members 20 and 34, and 22 and 38 wherein depending on whether the axial movement is contraction or elongation an opposite axial relative motion occurs between the pairs of cam mating members, that is, if plunger 34 elongates with respect to member 38, it elongates relative to its cam mating member 20, whereas member 38 contracts relative to its cam mating member 22.

This completes a cycle of operation of the tappet through its stages of contraction and elongation for the purpose of compensating for changes that may occur in the valve gear system with which the tappet is associated.

While this invention has been described in connection with certain specific embodiments of an internal combustion engine valve gear system, the principle involved is susceptible of numerous other applications that will readily occur to persons skilled in the art wherein an elongation or

contraction of an operating system requires automatic means to quickly compensate for changes in operating length. The invention is, therefore, limited only as indicated by the scope of the appended claims.

What I claim is:

1. In a mechanical self-adjusting mechanism, a plunger having a head at one end thereof and a cam surface at the other end thereof, a cylindrical member coupled to the plunger being solely axially movable relative thereto having a cam surface at one end thereof, a spring interposed between the plunger and cylindrical member and a pair of rigidly fixed members having cam surfaces for engagement respectively with the cam surfaces on the plunger and cylindrical member.

2. In a mechanical self-adjusting mechanism, a plunger having a head at one end thereof and a helical cam surface at the other end thereof, a cylindrical member coupled to the plunger axially moveable relative thereto having a helical cam surface at one end thereof, a spring interposed between the plunger and cylindrical member, and a pair of rigidly fixed members having helical cam surfaces for engagement respectively with the helical cam surfaces on the plunger and cylindrical member.

3. In a self-adjusting mechanism, a plunger having a head at one end thereof and a cam surface at the other end thereof, a cylindrical member coupled to the plunger axially moveable relative thereto having a cam surface at one end thereof, a spring interposed between the plunger and cylindrical member and a pair of rigidly fixed members having cam surfaces for engagement respectively with the cam surfaces on the plunger and cylindrical member, said engaging of cam surfaces being of equal pitch and complementary configuration.

4. In a self-adjusting mechanism, a plunger having a head at one end thereof and a cam surface at the other end thereof, a cylindrical member coupled to the plunger axially moveable relative thereto having a cam surface at one end thereof, a spring interposed between the plunger and cylindrical member and a pair of rigidly fixed members having cam surfaces for engagement respectively with the cam surfaces on the plunger and cylindrical member, the pairs of engaging cam surfaces on the integral members differing in pitch from the cam surfaces on the plunger and cylinder member.

5. In a self-adjusting mechanism, a plunger having a head at one end thereof and a cam surface at the other end thereof, a cylindrical member coupled to the plunger axially moveable relative thereto having a cam surface at one end thereof, a spring interposed between the plunger and cylindrical member and a pair of rigidly fixed members having cam surfaces for engagement respectively with the cam surfaces on the plunger and cylindrical member, the cam sur-

face on the plunger being angularly offset from the cam surface on the member coupled thereto and the cam surfaces on the integral members being in concentric radial alignment.

5. 6. In a mechanical self-adjusting mechanism, a plunger having a head at one end thereof and a cam surface at the other end thereof, a cylindrical member coupled to the plunger axially moveable relative thereto having a cam surface at one end thereof, a spring interposed between the plunger and cylindrical member and a pair of rigidly fixed members having cam surfaces for engagement respectively with the cam surfaces on the plunger and cylindrical member, said mechanism being adapted to increase and decrease in length upon relative rotation between the integral members and the cylindrical member and plunger.

20 7. In a mechanical self-adjusting mechanism, a plunger having a head at one end thereof and a cam surface at the other end thereof, a cylindrical member coupled to the plunger axially moveable relative thereto having a cam surface at one end thereof, a spring interposed between the plunger and cylindrical member and a pair of rigidly fixed members having cam surfaces for engagement respectively with the cam surfaces on the plunger and cylindrical member, said cylindrical member and plunger axially relatively moveable to one another upon rotation thereof

30 8. An automatic compensating device comprising a member having a pair of cam surfaces at one end thereof, a second member having a pair of cam surfaces for cooperation with the cam surfaces on the first member, and means associated with the members whereby upon rotation of one member relative to the other member an elongation or shortening of the over-all length of the compensating device occurs.

40 9. An automatic compensating device comprising a plunger, a cylinder associated with the plunger solely axially moveable relative thereto, resilient means biasing the cylinder and plunger apart, and means engaging the cylinder and plunger and angularly and axially movable relative thereto effective to provide for the elongation or shortening of the over-all length of the compensating device upon relative movement between the means and cylinder and plunger.
